(57) **CLAIM**

What is claimed is the ornamental design for a dip slip, as shown and described.

DESCRIPTION

FIG. 1 is a front top perspective view showing the dip slip of Applicant's new design.

FIG. 2 is a back bottom perspective view of the dip slip of FIG. 1.

FIG. 3 is a front plan view of the dip slip of FIG. 1.

FIG. 4 is a top plan view of the dip slip of FIG. 1; and,

FIG. 5 is a bottom plan view of the dip slip of FIG. 1.

The broken lines in the drawings show environment (e.g., a dip container) that forms no part of the claimed design.
